UNITED STATES PATENT OFFICE.

LEWIS W. EGGLESTON, OF BUFFALO, NEW YORK, ASSIGNOR TO AMERICAN RADIATOR COMPANY, OF NEW YORK, N. Y., A CORPORATION OF NEW JERSEY.

AIR-VENT VALVE FOR RADIATORS.

Application filed October 25, 1921. Serial No. 510,239.

- My invention relates to improvements in valves and particularly air vent valves for radiators. It has for one of its objects the provision of a simplified air valve which 5 will readily vent the air from the heating system without venting steam and without "throwing" water; which may be cheaply made and the parts thereof readily assembled.
- 10 The invention consists in the improvements to be fully described hereinafter and the novelty of which will be particularly pointed out and distinctly claimed. I have fully and clearly illustrated my invention in 15 the accompanying drawings, to be taken as a part of this specification and wherein:—

- Figure 1 is a sectional view of an air valve embodying my invention;
- Fig. 2 is a sectional view taken on the line 20 2—2 of Fig. 1;
- Fig. 3 is a sectional view taken on the line 3—3 of Fig. 1;
- Fig. 4 is a sectional view taken on the line 4—4 of Fig. 1;
- 25 Fig. 5 is an enlarged detailed section showing the vent opening and the valve therefor; and
- Fig. 6 is a detailed section of a modification of my invention.

- 30 Referring to the drawings, in the embodiment illustrated I provide a casing comprising base 1 and a top 2. The base 1 at its top is cylindrical in form and is internally screw-threaded as at 2^a to receive the top. The base, at the bottom of the screw-threaded portion, is provided with an annular seat 3, the purpose of which will more fully hereinafter appear, and below the seat the opposite sides of the base are flattened 35 and drawn in or inclined toward each other to form a narrow rounded channel 3^a, as shown in Fig. 2. Extending transversely of the base and into the channel 3^a is a tubular nipple 4 which snugly fits the rounded portion of said channel, said nipple being additionally held in position by solder or by brazing, and having its inner open end communicating with the said channel which forms a settling basin for dirt, grit, etc. The 40 outer end of this nipple 4 is screw-threaded at 4^b to engage in the threaded tapping 4^c in the radiator wall 5 and the inner portion of the nipple at its top is provided with an air inlet opening 6.
- 45 Passing through this nipple 4 and extend-

ing into the channel 3^a is a siphon tube 7 which is adapted to project into the radiator as shown in Fig. 1, said tube having its inner end within the body 1, spun or flared outwardly at 7^a to prevent its withdrawal 60 from the nipple and at the same time permitting a swiveling and slight longitudinal movement. The nipple 4 at its inner end has a lip or lug 4^a formed on its under side which prevents the raising of the siphon 65 against the top of the nipple and thereby affords a clear passage through the nipple above the siphon. The tube 7 serves a purpose, during the normal operation of the valve, to be more fully described herein- 70 after.

The main body portion of the top 2 of the casing is preferably cylindrical in form and at its upper end merges into a conical portion 2^b, which, in turn, at its upper portion merges into a more abrupt conical portion 10 (see Fig. 5), provided at its central portion with an air vent opening 9 formed by a perforation made through the apex of said conical portion 10. By widely flaring 80 or tapering the casing, as at 10, adjacent the vent opening, the point 11 of the valve 12, to be hereinafter described, will seat on the edge only of the opening 9, thus providing a contact of small area between the 85 valve and its seat, and preventing the collection of drops of water at this point between the stem and the adjacent parts of the casing. This arrangement just described prevents water from being sprayed out of 90 the opening when the valve moves from closed to open position.

For operating the valve I provide a hollow thermostatic float 13 having a rounded top wall provided with a socket 14 into which the lower end of the stem 12^a of the valve 12 is soldered, and said thermostatic float having an inwardly dished flexible bottom wall 13^a preferably having annular concentric corrugations 13^b therein. A 95 guide and stop for the float is provided and comprises a pair of arcuate plates 15 connected to each other by a cross piece 16, and having their outer edges clamped between the lower edge of the casing top 2 and the shoulder or seat 3. A screw 17 extends through an opening in the cross piece 16 to provide an adjustable stop, and fingers 18 upwardly extending, on the plates 15 provide guides for the float. The outer edges 105 110

of the fingers engage the inner walls of the casing and properly center the guide.

The structure is such that the parts are readily assembled and the valve spaced relative to its seat at the factory. In assembling the structure the casing top is turned upside down and the float dropped into the top, the valve seating itself due to the shape of the top, the guide is then inserted in the top, and the threaded screw 17 turned up to insure the proper seating of the valve, then given sufficient turn back, preferably about a half turn, to space the valve from its seat to give the correct open position for the valve, after which a drop of solder is placed on the stop to prevent it from working loose. The assembled guide casing and float are then placed in position on the base into which has been secured the nipple 4 with its siphon 7 and the top is screwed down to seat the guide on the shoulder.

The operation of the valve is as follows:— Prior to assemblage the hollow float is charged with a suitable volatile which at a predetermined temperature will volatilize to generate sufficient pressure in the float to outwardly bow the inwardly dished bottom of the float and thereby raise the float to close the valve.

When the radiator to which the valve is connected is cold the valve will be in position as in Fig. 1 with the vent open. When steam is admitted to the radiator the inflowing steam forces ahead of it the air which has accumulated in the radiator sections and the air passes through the nipple 4 up through the casing between the walls of the float and casing and out through the vent opening.

As long as cold air only passes through the valve the float will remain down and the inwardly dished bottom contracted thereby leaving the valve open. As soon, however, as the steam following the air strikes the thermostatic float 13 the heat of the steam volatilizes the liquid in the thermostatic float, outwardly bowing the bottom of the float which causes the float to rise and closes the valve port 9 against the passage of steam.

It frequently happens that during the escape of air from the radiator the water of condensation in the radiator surges up therein and tends to flow out through the valve. As soon as a "slug" of water surges into the valve casing the water rising in the casing causes the float to rise closing the vent opening thus preventing the escape of water therethrough, the float remaining up until the water recedes. The water of condensation of a radiator during the admission of steam therein surges back and forth and upon the rearward or inward surge of the water it will be siphoned out of the valve casing through the siphon tube 7 and at the same time air will pass into the casing

through the passage in the nipple around the siphon tube and up into the valve. As the water drains out of the casing the air passes in and out through the vent until eventually the valve is closed off by steam coming in contact with the thermostatic float.

I have found in operation that unless the float 13 is properly spaced with relation to the walls of the casing 2, that is, unless sufficient area is provided between the wall of the float and the wall of the casing, after the water has receded from the casing, a film of water will remain between the wall of the float and the wall of the casing, being held therein by capillary attraction. This film if permitted to exist forms a seal around the float and prevents the passage of air above the float thus causing a partial vacuum which prevents the float from dropping to open the valve.

However, if the area between the walls of the float and casing is properly proportioned so that the water will not be held by capillarity to form a seal, the float will drop with the receding of the water from the casing, promptly opening the valve to permit the passage of air through the vent opening and the valve will not become "water logged". In actual practice in a valve of the size illustrated in the drawings, which are full size, a spacing of one eighth of an inch between the wall of the casing and wall of the float has given satisfactory results. When the pressure behind the water in the base drops, the siphon or drain tube 7 will operate to cause the water to flow out of the base, and at the same time air will pass into the valve casing through the nipple and around the tube. This structure including the tube 7 is particularly designed for use in the eighth inch tapping (Briggs standard) which is at present the standard tapping for radiator air valve nipples.

Another method for accomplishing the same result is to provide a sufficiently large opening in the nipple and into the radiator. If this tapping be increased sufficiently to accommodate a larger sized nipple the water will escape from the valve and at the same time air will enter the valve. I have found by experiment that a three-eighths inch tapping (Briggs standard) will obtain satisfactory results and that with this increased area the siphon tube may be dispensed with. It is understood, however, that with the larger sized tapping the spacing between the wall of the float and the wall of the casing need not be changed.

It is therefore optional to use the one-eighth inch tapping with a siphon tube as illustrated in Fig. 1 or to use a three-eighths inch tapping without the siphon as illustrated in Fig. 6, as with both these structures I am enabled to obtain satisfactory results.

I have also found that the effective area of the vent opening and the weight of the valve and float affect the opening of the valve and should be properly proportioned to cause the valve to open under a predetermined constant pressure, after it has once closed. Due to the fact that there is a differential of pressure between the exterior and interior of the valve casing the weight of the float and valve must be sufficient to overcome by gravity the power exerted upon the area of the valve exposed to the atmosphere through the vent opening. Therefore, in order that the valve will open with air in the casing and at a predetermined boiler pressure, this weight and area should be properly proportioned and the weight tending to open the valve should be greater than the area of the vent opening times the pressure in the valve casing.

In a structure of the size illustrated I have obtained satisfactory results with a pressure in the casing of approximately ten pounds by making the combined weight of the valve and float about six and one half grams.

In order to prevent water from spraying through the vent opening I have provided sufficient spacing above the float to form a separating chamber. In the structure illustrated the distance between the float and top of the casing is approximately one and five sixteenths inches which provides a sufficient height above the float to permit the water and dirt to drop by gravity before it reaches the vent thus preventing "spraying" of the valve.

It will be noted from the above description taken in connection with the drawings, that the thermostatic float member is at all times during the normal operation of the valve located in the lower part of the body portion 2, so as to provide an efficient separating chamber above said member, and the valve stem is made relatively slender or of small cross-section so as to provide a chamber of considerable volume above said member. By the arrangement just described, in the event the valve casing should contain water insufficient in quantity to cause the float to close the valve, and air from the radiator should pass up through the water, there will be a sufficient amount of space above the surface of the water to permit the air to be liberated and pass out of the casing without carrying water with it. When the conditions in the radiator are such that the water may recede from the valve casing, the water flows from the base of the casing promptly, in view of the fact that its flow is not retarded by any capillary attraction within the valve casing, between the float and the casing, or elsewhere, and the drain tube 7 assists in and assures prompt flow through the outlet nipple.

Having thus described my invention what

I claim as new and desire to secure by Letters Patent is:

1. An air relief valve for radiators comprising a casing having a substantially cylindrical body portion, and a port connection adapted to communicate with a radiator and said casing having a conical upper end wall provided with a vent opening at its apex, a closed thermostatic float member arranged in the lower portion of said cylindrical body portion and containing a volatile liquid, said float member having a flexible lower wall, a valve stem connected to said thermostatic float member and extending through said cylindrical portion and provided at its upper end with a valve part to cooperate with said vent opening to open and close the same, the side wall of said thermostatic float member being spaced from the wall of said casing a distance sufficient to preclude holding of water by capillary attraction between said float member and casing wall, and the interior of the cylindrical and conical portions of the casing above said float member being of sufficient height and volume to constitute a separating chamber, and a guide member for said float arranged beneath the float and having spaced guide members extending upwardly between the side wall of the float and the casing.

2. An air relief valve for radiators comprising a casing having a substantially cylindrical body portion having an upward tapering conical upper end wall, said end wall having a central vent opening formed by a perforation through the apex of said conical portion, a closed thermostatic float member arranged in the lower portion of said casing and containing a volatile liquid, and a valve stem connected to said float member and provided at its upper end with a valve part formed to make edge contact with the casing wall surrounding said vent opening, said conical upper wall being flared widely relative to said point of contact of said valve part to prevent adhesion of water between said wall adjacent said opening and stem, and the interior of said casing being of sufficient capacity above said float member to constitute a separating chamber.

3. An air relief valve for radiators comprising a casing including a vent opening therein, a valve for controlling said vent opening, a closed thermostatic float in said casing and adapted to operate said valve, and a guide for said float comprising a member arranged beneath the float and having upwardly-extending guide fingers extending between the outer face of the float and the wall of the casing, said guide fingers cooperating with the outer face of the float.

4. An air relief valve for radiators, comprising a casing including a base and top, the base having a channel in the bottom thereof and a stem fitting said channel and

occupying a portion only thereof and having an open end communicating with the rest of the channel, said stem projecting through the base for connecting the valve with a radiator.

5. An air relief valve for radiators comprising a casing including a base and top, the base having opposite sides flattened and drawn in toward the bottom to form a channel, and a hollow stem fitting within said said channel and projecting through the base for connecting the valve with a radiator.

10. An air relief valve for radiators comprising a casing including a base and top, said top having a vent opening therein, a valve for controlling said opening, a float operating said valve, and a guide for said float comprising a pair of arcuate plates 20 clamped between the base and top and having upwardly extending guide fingers.

15. An air relief valve for radiators comprising a casing including a base and a top, said top having a vent opening therein, a valve, a float operating said valve, and a stop member for said float having guide fingers fitting within the top, and having a centrally disposed adjustable stop.

20. An air relief valve for radiators comprising a casing including a base and a top, a valve, a float operating said valve, and a guide for said float comprising an arcuate plate clamped between the top and base of the casing and having upwardly extending guide fingers fitting within the top.

25. An air relief valve for radiators comprising a casing including a base and a top, a valve, a float operating said valve, and a stop member for said float having guide fingers fitting within the top, and having a centrally disposed adjustable stop.

30. An air relief valve for radiators comprising a casing including a base and top, a valve, a float operating said valve, and a member clamped between the top and base of the said casing, said member having upwardly extending positioning fingers cooperating with the float, and an adjustable stop.

35. In witness whereof, I have hereunto subscribed my name.

LEWIS W. EGGLESTON.
